UNITED STATES PATENT OFFICE.

WALTER H. STROMEYER, OF NEW YORK, N. Y.

TOBACCO-POUCH.

1,156,720.

Specification of Letters Patent. Patented Oct. 12, 1915.

Application filed October 23, 1914. Serial No. 868,224.

To all whom it may concern:

Be it known that I, WALTER H. STROMEYER, a citizen of the United States, and a resident of the city of New York, borough 5 of the Bronx, in the county of Bronx and State of New York, have invented a new and Improved Tobacco-Pouch, of which the following is a full, clear, and exact description.

10 The object of the invention is to provide a new and improved tobacco pouch, more especially designed for the use of smokers of cigarettes and arranged to securely hold the tobacco and superimposed sheets of 15 cigarette paper, and to allow the user to readily discharge the tobacco in stream form and in any desired quantity from the pouch onto a sheet of cigarette paper without danger of spilling the tobacco, at the same 20 time facilitating the distribution of the tobacco on the paper preparatory to the final production of the cigarette.

In order to accomplish the desired result, use is made of a sheet of flexible material, 25 a pocket extending transversely on the inner face of the said sheet, the pocket having a mouth at one side of the sheet, and a fastening device for closing the mouth to confine the tobacco in the pocket, the mouth 30 when in open position allowing the tobacco to pass out of the pocket in a stream on pressing the edges of the pocket toward each other with a view to forming a portion of the pocket into a chute leading to the open 35 mouth.

A practical embodiment of the invention is represented in the accompanying drawings forming a part of this specification, in which similar characters of reference indicate corresponding parts in all the views.

Figure 1 is a perspective view of the tobacco pouch in position for delivering tobacco to a sheet of cigarette paper, Fig. 2 is a perspective view of the tobacco pouch 45 with the closing flap in open position; Fig. 3 is a sectional side elevation of the tobacco pouch with the parts in closed position; Fig. 4 is a cross section of the same; Fig. 5 is a plan view of the sheet material for forming the pocket and the lining for the closing flap; Fig. 6 is a face view of the sheet material for forming the body of the tobacco pouch; and Fig. 7 is a face view of one of the gussets used on the pocket.

55 The tobacco pouch is in the form of a

wallet and its body A is made from a piece of sheet material such as leather and the like, and across the inner face of the body A extends a pocket B adapted to contain tobacco C, the pocket B being formed of a 60 piece of canvas or other flexible material, sewed or otherwise fastened to the body A along the sides and one end and along a portion at the other end so as to leave a mouth B' at one side of the body A for the passage of the tobacco from the pocket B. The mouth B' is provided with fastening members D, preferably in the form of a socket and a stud, attached to the inner face of the mouth approximately midway between the 65 sides of the mouth. By this arrangement the mouth B' can be closed to prevent the tobacco from passing accidentally out of the pocket, and when the fastening members are disengaged from each other the mouth 70 can be opened to permit of filling the pocket B with tobacco and to allow of discharging the tobacco from the pocket by way of the said mouth, as indicated in Fig. 1. The body A is preferably provided along its 75 edges with a suitable binding E which also embraces approximately one-half portion of the side of the pocket B having the mouth B' so that only one-half portion of its side forms the mouth B' of the pocket, and this 80 half portion of the pocket B is provided with a binding E', as plainly indicated in Fig. 2. The material forming the pocket B is extended to form a lining B² for a closing flap A' formed of one end of the sheet 85 of the body A, and on this lining B² is secured a holder F, preferably in the form of an elastic band, for holding the superimposed sheets of cigarette paper G securely in 90 position on the lining of the closing flap A'. By the arrangement described the uppermost sheet of cigarette paper can be readily removed from the pile and bent into trough shape to permit of readily dropping the tobacco onto the sheet from the pocket 95 B when holding the patch in position, as indicated in Fig. 1. The other end A² of the body A is bent back upon a portion of the pocket B adjacent the mouth B' and the sides of this bent-back end A² are connected 100 by gussets H with the pocket B and the body A so as to form a receiving pocket for the reception of the free end of the closing flap A' to hold the said closing flap in closed 105 position when the pouch is not in use. In 110

order to facilitate the passage of the free end of the closing flap into the said receiving pocket formed by the end A², the sides of the closing flap A' are preferably made 5 tapering, as plainly indicated in Figs. 2 and 6. By the use of the gussets H the pocket portion B underneath this end A² can be readily filled with tobacco as the gussets H are free to yield the same as the sides, one 10 end and the closed portion of the other end of the pocket B to accommodate a large quantity of tobacco in the pocket B.

In using the pouch the pocket B is filled 15 with tobacco, as previously explained, and the sheets of cigarette paper G are placed under the elastic band F, and when the pouch is not in use the mouth B' of the pocket B is closed by the fastening device D, and the free end of the closing flap A' 20 is placed under the end A² so as to quickly hold the pouch in closed position. When it is desired to use the pouch for forming a cigarette the user opens the closing flap A', then removes the uppermost sheet of cigarette 25 paper from under the band F, and then opens the mouth B' by disengaging the members of the fastening device D from each other. The user now holds the pouch in his hand to press the edges thereof toward 30 each other so that the mouth B readily opens to allow the tobacco to pass stream-like out of the pocket B onto the sheet of cigarette paper G held below the mouth, as indicated in Fig. 1. By the arrangement described 35 the tobacco can be readily distributed on the cigarette paper without danger of spilling the tobacco, and when the desired amount of tobacco has been placed on the cigarette paper, the user closes the fastening members 40 of the closing device D, and then finishes the cigarette by rolling the tobacco in the sheet in the usual manner.

Having thus described my invention, I claim as new and desire to secure by Letters 45 Patent:

1. A tobacco pouch in the form of a wallet having a transverse pocket for the reception of the tobacco, the pocket being secured along its sides and one end to the body 50 of the wallet, and secured along a portion of the other end so as to form a restricted mouth at said end, the mouth of said pocket being at one side of the wallet and having a closing device intermediate the sides of 55 the mouth to allow of closing or opening the mouth, the mouth when in open position forming an outlet for the tobacco and the said pocket, when the edges are pressed toward each other forming a chute leading 60 to the open mouth.

2. A tobacco pouch, comprising a sheet of flexible material, a pocket extension terminating on the inner face of the sheet and adapted to hold tobacco, the pocket having 65 its mouth at one side of the sheet, a fasten-

ing device for closing the mouth intermediate of its sides, the mouth when open forming an outlet for the tobacco, a flap formed at one end of the sheet, and a receiving pocket for the flap at the other end of the sheet. 70

3. A tobacco pouch, comprising a sheet of flexible material, a pocket extending transversely on the inner face of the sheet and adapted to hold tobacco, the pocket having 75 its mouth at one side of the sheet, a fastening device for closing the mouth intermediate of its sides, the mouth when open forming an outlet for the tobacco, the said sheet having one end forming a flap extending beyond the pocket, and a holding device on the said flap for holding a package of cigarette paper. 80

4. A tobacco pouch, comprising a sheet of flexible material, a pocket extending 85 transversely on the inner face of the sheet and adapted to hold tobacco, the pocket having its mouth at one side of the sheet, and a fastening device for closing the mouth intermediate of its sides, the mouth when open 90 forming an outlet for the tobacco, one end of the said sheet being bent back upon the outer face of a portion of the pocket and having its sides fastened thereto, the other end of the said sheet forming a closing flap 95 adapted to be passed with its free end under the said other end.

5. A tobacco pouch, comprising a sheet of flexible material, a pocket extending transversely on the inner face of the sheet and 100 adapted to hold tobacco, the pocket having its mouth at one side of the sheet, a fastening device for closing the mouth intermediate of its sides, the mouth when open forming an outlet for the tobacco, one end of 105 the said sheet being bent back upon the outer face of a portion of the pocket and having its sides fastened thereto, the other end of the said sheet forming a closing flap adapted to be passed with its free end under 110 the said other end, and a holding device on the inner face of the said closing flap for holding a package of cigarette paper. 110

6. A tobacco pouch, comprising a sheet of flexible material, a tobacco pocket extending 115 transversely on the inner face of the said sheet and spaced from the ends thereof, the pocket having a mouth at one side of the sheet, the mouth being of a width corresponding approximately to one-half of the width of the pocket, a fastening device for closing the mouth, and a closing flap at one end of the sheet, the other end of the sheet being formed into a receiving pocket for the end of the closing flap. 120

7. A tobacco pouch, comprising a sheet of flexible material, a tobacco pocket extending transversely on the inner face of the said sheet and spaced from the ends thereof, the pocket having a mouth at one side of the sheet. 125

sheet, the mouth being of a width corresponding approximately to one-half of the width of the pocket, a fastening device for closing the mouth, one end of the sheet being bent back upon the tobacco pocket adjacent to the mouth and being fastened along its sides, the other end of the sheet forming a closing flap adapted to fold under the return bent end, and an elastic band on the inner face

of the closing flap for holding cigarette paper.

In testimony whereof I have signed my name to this specification in the presence of two subscribing witnesses.
